US00D703270S

(12) **United States Design Patent**
Dyer

(10) **Patent No.:** **US D703,270 S**
(45) **Date of Patent:** **** Apr. 22, 2014**

(54) **ERGONOMIC HANDLE**

(76) Inventor: **Edward P. Dyer**, Germantown, WI (US)

(**) Term: **14 Years**

(21) Appl. No.: **29/431,765**

(22) Filed: **Sep. 11, 2012**

Related U.S. Application Data

(63) Continuation-in-part of application No. 29/392,188, filed on May 18, 2011, now Pat. No. Des. 667,054.

(51) **LOC (10) Cl.** **19-06**

(52) **U.S. Cl.**

USPC **D19/178**; D19/920

(58) **Field of Classification Search**

USPC ..... D14/411; D19/35, 36, 41-51, 54-58; 24/11 F, 11 P, 11 R; 401/52, 99-109, 401/192, 195, 196; 16/430; D8/107, 300

See application file for complete search history.

(57) **CLAIM**

The ornamental design for an ergonomic handle, as shown and described.

DESCRIPTION

FIG. 1 is a perspective view of a first embodiment of my invention;

FIG. 2 is another perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof;

FIG. 8 is a back elevation view thereof;

FIG. 9 is a perspective view of a second embodiment of my invention;

FIG. 10 is another perspective view thereof;

FIG. 11 is a top plan view thereof;

FIG. 12 is a bottom plan view thereof;

FIG. 13 is a right side elevation view thereof;

FIG. 14 is a left side elevation view thereof;

FIG. 15 is a front elevation view thereof; and,

FIG. 16 is a back elevation view thereof.

The broken line showings in FIGS. 1-16 are for illustrative purposes only and form no part of the claimed design.

1 Claim, 6 Drawing Sheets
